VENTILATED TUYÈRE

William A. Riddell, Frederick, Md., assignor to
The General Engineering Company, Frederick,
Md., a corporation of Maryland

Application May 18, 1936, Serial No. 80,444

8 Claims. (Cl. 110—44)

My invention relates broadly to furnaces and more particularly to an improved construction of ventilated tuyère for furnaces.

One of the objects of my invention is to provide a construction of ventilated tuyère for furnaces having means for reducing the tendency of the tuyère to be burned out under conditions of high temperature furnace operation.

Another object of my invention is to provide a construction of tuyère having means for uniformly distributing air beneath the fire bed while eliminating the tendency of blowing holes in the fire bed.

Still another object of my invention is to provide a construction of tuyère formed from a casting having a relatively thin wall shaped to distribute air under pressure radially from a substantially central position beneath the plate and in a relatively narrow confined zone extending in a plane beneath the plate substantially parallel with the plane of the plate.

A further object of my invention is to provide a construction of tuyère having passages therethrough for the recirculation of air currents tending to maintain the tuyère at a safe operating temperature and independently of the distributing means for delivering air under pressure beneath the fire bed.

Another object of my invention is to provide a construction of tuyère having elongated slotted self-clearing air passages therein.

A still further object of my invention is to provide a construction of ventilated tuyère having a multiplicity of radially extending deflecting members immediately beneath the tuyère plate for directing air beneath the fire bed in a prepatterned zone extending in a plane substantially parallel with the plane of the tuyère.

Other and further objects of my invention reside in an improved construction of cast tuyère as set forth more fully in the specification hereinafter following by reference to the accompanying drawings, in which:

Figure 1 is a plan view showing a group of tuyères constructed in accordance with my invention and assembled in operating relation; Fig. 2 is a longitudinal sectional view taken on line 2—2 of Fig. 1 and illustrating the superimposed relation of the group of tuyère plates shown therein; Fig. 3 is a front end view of the group of tuyères illustrated in Figs. 1 and 2; Fig. 4 is a bottom plan view of the tuyère plate of my invention; Fig. 5 is an end elevational view of the tuyère plate shown in Fig. 4; and Fig. 6

is a longitudinal view through the tuyère plate taken on line 6—6 of Fig. 4.

Referring to the drawings in detail, reference character 1 indicates a tuyère plate embodying my invention. The tuyère plate 1 is illustrated in assembled superimposed relation with respect to three similarly formed tuyère plates. For purposes of interlocking the tuyère plates, each tuyère plate is provided with a centrally positioned substantially rectangular aperture 2 provided with a shoulder 3 adjacent the forward end thereof. Each tuyère plate is provided with a depending member 4 connected therewith having a hook-shaped end portion 5 thereon directed toward the front of the tuyère plate. A strengthening web 6 is provided immediately behind the depending member 4 and extending to the shoulder 3 of the tuyère plate. The lower surface of the tuyère plate 1 immediately adjacent the central aperture 2 is tapered upwardly and terminates in a substantially thinner rearwardly projecting portion of the tuyère plate as shown. The rearwardly projecting portion of the tuyère plate 1 terminates in an inwardly curved edge indicated at 8. The rearwardly projecting portion of the tuyère plate 1 is symmetrically apertured at 9. In the foregoing description and herein-after, I refer to the front of the tuyère plates as that portion which is exposed and seen when viewing an assembled grate, namely the portion terminating at the edge 18.

For purposes of insuring the recirculation of air through the tuyère plates and the maintenance of the tuyère plates at relatively safe operating temperatures, I provide substantially segmental shaped or curved slots 10 in the plate 1. The slots 10 are separated at the central longitudinal axis of the plate by a strengthening web portion of the plate. The slots 10 are curved to substantially conform in shape to the perimeter of the tuyère plate 1 indicated generally at 16 from which the tuyère plate is inclined to a terminating curved edge shown at 18 along an inclined surface which I have indicated at 17. The tuyère plate 1 is relatively thin and is supported by a pair of depending side walls of substantially the same thickness as indicated at 12. The depending walls 12 each contain passages 13 extending therethrough and terminate in end portions indicated at 15.

I provide a multiplicity of radially extending ribs 19 immediately beneath the tuyère plate 1. The ribs 19 are each formed on an angle as represented at 20 and are rounded to offer minimum obstruction to the passage of air while guiding

the air over a fan-shaped area in a confined zone immediately beneath the tuyère plate. For purposes of additionally cooling the tuyère plate, I provide apertures 21 in the horizontal portion 5 of the tuyère plate and between the sets of deflecting plates or supporting ribs 19. The apertures 21 are so positioned that air is directed upwardly immediately against the lower surface of the inclined plane portion 17 of the tuyère 10 plate immediately above. The inclined portion 17 of the tuyère plate is directed toward the horizontal portion of the lower adjacent tuyère plate providing a confined zone 22 for the passage of air. That is to say, a narrow zone is 15 provided for the distribution of air in a plane substantially parallel with the plane of the tuyère plate. The exit for air beneath the tuyère plate is narrow in cross-sectional area immediately above an adjacent lower tuyère plate through 20 which air is adapted to be forced in a blast directed against the lower surface of the inclined portion 17 of the tuyère plate immediately above the apertured tuyère plate. The radial position of ribs 19 is such that air is distributed in a 25 fan-like direction from the tuyère plate. A pair of ribs 19 extend adjacent each other on opposite sides of the center line of the tuyère plate and are symmetrically distributed beneath the tuyère plate as shown more particularly in Fig. 30 4. The ribs 19 are spacially related to form substantially rectangular channels beneath the tuyère plate. The channels established between the ribs 19 are proportioned so that the transverse dimension thereof is not less than twice the 35 thickness of the adjacent ribs 19.

The tuyère plates are readily superimposed with respect to each other as illustrated in Figs. 1, 2 and 3 and may be individually replaced as required. In order to explain the superimposed 40 relation of the plates, I have shown the similarly formed plates as identified by similarly numbered reference characters having the subscripts *a*, *b* and *c* applied thereto, that is to say, the tuyère plate immediately below the tuyère 45 plate which has been described in detail terminates in a peripheral edge portion indicated at 18a. The next adjacent lower tuyère plate terminates in a peripheral edge 18b. The tuyère plate beneath the last mentioned peripheral edge 50 is indicated at 18c. As represented in Fig. 3, the ribs of the several tuyère plates 1, 1a, 1b and 1c are aligned with each other so that air is distributed in zones substantially parallel with the planes of the respective plates. The relatively 55 thin construction of the tuyère plates serves to reduce cost in manufacture and facilitates cooling of the plates, thereby maintaining the operating temperature of the plates relatively low.

The improved distribution of air obtainable 60 with the tuyère plates of my invention insures a more uniform firebed. The elongated slots 10 and apertures 21 tend to maintain a balanced air pressure under the firebed. As indicated in Fig. 1, the slots 10 in a lower tuyère plate of an assembly 65 are disposed substantially in coincidence with a number of the apertures 21 in the next upper plate so that air pockets are prevented from accumulating and causing overheating. Complete circulation of air behind and substantially 70 parallel to the exposed portions of the tuyère plates is thus, assured, as well as more positive distribution at equal pressure of air fed from the tuyère plate. In addition, in case the air passages between the ribs 19 become plugged, air 75 is permitted to be forced up between the tuyère

plates to maintain the plates relatively cool. The advantages of the elongated slots 10 are that should one end of the slots become plugged, the other end ordinarily tends to remain open and enables the plugged portion to be blown open or blown free of any packed or accumulated matter. 5

The fact that the width of the channels between the ribs 19 is never less than twice the thickness of the adjacent rib 19 insures a wide aperture beneath the plate which tends to act in 10 a self-cleaning manner in case it does become clogged. The recirculation of cooling air currents may be maintained through the passages 13, 10, 2 and 21 insuring the maintenance of 15 safe temperatures under operating conditions of the tuyère plates. The fact that blasts of air are directed immediately adjacent the lower surface of the peripheral portion 18 of the tuyère plate increases the protection afforded to the material of the tuyère plate against the action of 20 excessive temperatures.

While I have described the tuyère plate of my invention in that form which has proven very practical and successful in actual use, I am fully aware that modifications may be made in the 25 construction and arrangement of parts in the tuyère plate of my invention. Accordingly, I intend no limitations upon my invention except as may be imposed by the scope of the appended 30 claims.

What I claim as new and desire to secure by Letters Patent of the United States is as follows:

1. A tuyère plate comprising a plate member having, in its operative position, a substantially flat top portion and a downwardly inclined 35 curved peripheral portion, a multiplicity of air directing members relatively angularly disposed immediately beneath the inclined portion of said plate for directing air in a substantially fan-like zone beneath said plate in approximately rectangular shaped channels, and side walls for supporting said plate, said plate having passages extending therethrough normal to the flat portion thereof and between said air directing members, and the flat portion of said plate having a pair 40 of arcuate shaped passages therethrough.

2. A tuyère plate comprising a casting having, in its operative position, a pair of depending side portions and a relatively flat top portion terminating in a curved portion, a downward inclined 50 portion extending from said curved portion and terminating in a curved edge formed on a different center, a plurality of relatively angularly disposed air directing members disposed beneath said flat top portion and said inclined portion 55 and defining approximately rectangular channels for air beneath said plate having a transverse width not less than twice the lateral thickness of said air directing members, said top portion having passages for air extending therethrough 60 normal thereto and between said air directing members and a pair of segmental shaped passages therethrough.

3. A tuyère plate comprising a plate member having, in its operative position, a substantially flat top portion and a downward inclined curved peripheral portion, a multiplicity of air directing members relatively angularly disposed immediately beneath the inclined portion of said plate for directing air in a substantially fan-like zone 70 beneath said plate in approximately rectangular shaped channels, and side walls for supporting said plate, said plate having passages extending therethrough normal to the flat portion thereof and between said air directing members, and the 75

flat portion of said plate having an elongated passage for air extending therethrough on one side of the central longitudinal axis thereof intermediate the respective side wall and said axis and adjacent the inner ends of a predetermined number of said air directing members.

4. A tuyère plate comprising a casting having, in its operative position, a pair of depending side portions and a relatively flat top portion terminating in a curved portion, a downward inclined portion extending from said curved portion and terminating in a curved edge formed on a different center, a plurality of relatively angularly disposed air directing members disposed beneath

said flat top portion and said inclined portion and defining approximately rectangular channels for air beneath said plate having a transverse width not less than twice the lateral thickness of said air directing members, said top portion having passages for air extending therethrough normal thereto and between said air directing members, and elongated passages for air extending therethrough adjacent the inner ends of the relatively angularly disposed air directing members.

5. A tuyère plate comprising a plate member having, in its operative position, a substantially flat top portion and a downward inclined curved peripheral portion, a multiplicity of air directing members relatively angularly disposed immediately beneath the inclined portion of said plate for directing air in a substantially fan-like zone beneath said plate in approximately rectangular shaped channels, and side walls for supporting said plate, said plate having passages extending therethrough normal to the flat portion thereof and between said air directing members, and the flat portion of said plate having elongated passages for air extending therethrough and disposed on opposite sides of the longitudinal central axis of said plate and extending adjacent the inner ends of the air directing members.

6. A tuyère plate comprising a casting having, in its operative position, a pair of depending side portions and a relatively flat top portion terminating in a curved portion, a downward inclined portion extending from said curved portion and terminating in a curved edge formed on a different center, a plurality of relatively angularly disposed air directing members disposed beneath said flat top portion and said in-

clined portion and defining approximately rectangular channels for air beneath said plate having a transverse width not less than twice the lateral thickness of said air directing members, said top portion having passages for air extending therethrough normal thereto and between said air directing members and having elongated passages for air extending therethrough and disposed on opposite sides of the longitudinal central axis of said plate, and extending from positions adjacent the respective depending side portions to positions adjacent the central axis of said plate at the inner ends of the air directing members.

7. In combination, at least two tuyère plates each comprising a casting, having in operative position, a flat top portion and an inclined lip portion extending from said top portion and terminating in a curved edge, said lip portion having the under surface thereof inclined parallel to the upper surface thereof, a plurality of relatively angularly disposed ribs beneath the casting for directing air outwardly under the inclined lip portion; said plates being arranged in superimposed, longitudinally relatively displaced position, and the lower one of said plates being apertured in the flat top portion thereof between adjacent ribs and beneath the inclined lip portion of the upper one of said plates.

8. In combination, at least two tuyère plates each comprising a casting, having in operative position a flat top portion and an inclined lip portion extending from said top portion and terminating in a curved edge, said lip portion having the under surface thereof inclined parallel to the upper surface thereof, a plurality of relatively angularly disposed ribs beneath the casting for directing air outwardly under the inclined lip portion; said plates being arranged in superimposed, longitudinally relatively displaced position, and having apertures in the flat top portions thereof between adjacent ribs, the apertures in the lower one of said plates being disposed beneath the inclined lip portion of the upper one of said plates, and the lower one of said plates having elongated apertures on either side of the longitudinal central axis thereof substantially in alignment with a number of the aforesaid apertures in the upper one of said plates.

WILLIAM A. RIDDELL. 50
